DESIGN FOR A TOY ANIMAL FIGURE OR SIMILAR ARTICLE

Mary Lu Quinby, Los Angeles, Calif.

Application July 11, 1946, Serial No. 131,510

Term of patent 14 years

(Cl. D34—2)

To all whom it may concern:

Be it known that I, Mary Lu Quinby, a citizen of the United States, residing at Los Angeles, in the county of Los Angeles and State of California, have invented a new, original, and ornamental Design for Toy Animal Figure or Similar Article, of which the following is a specification, reference being had to the accompanying drawing forming a part thereof.

I claim:

The ornamental design for a toy animal figure or similar article, substantially as shown.

MARY LU QUINBY.
